Patented June 20, 1922.

FIG. 2.

Inventor.

F. N. Hallett.

by Fred P. Grinn
his Atty.

UNITED STATES PATENT OFFICE.

FRED N. HALLETT, OF SEATTLE, WASHINGTON, ASSIGNOR TO THE CONSTRUCTION APPLIANCE CO., A CORPORATION OF WASHINGTON.

BOLTING-UP DEVICE.

1,420,424.

Specification of Letters Patent. Patented June 20, 1922.

Application filed December 17, 1919, Serial No. 345,574. Renewed February 10, 1922. Serial No. 535,617.

To all whom it may concern:

Be it known that FRED N. HALLETT, a citizen of the United States, residing at Seattle, in the county of King and State of Washington, has invented certain new and useful Improvements in Bolting-Up Devices, of which the following is a specification.

This invention relates to an improved means for drawing plates or the like together and holding them in such position to permit further work thereon, as riveting them together.

The improved machine provides a means for exerting a direct drawing action upon one of such plates while the action is held relatively fixed, the device operating under fluid pressure and through the application of a wedge for such drawing action.

In the drawings:

20 Figure 1 is a plan of the machine shown as connected with the plates to be operated upon.

Figure 2 is a plan of the same.

The improved machine comprises a base 25 1, having uprights 2 and a table portion 3.

The table 3 is formed with spaced openings 4, to receive rod portions 5 of a pull-frame 6. The upper ends of the rods 5 are connected by a cross-bar 7, and their lower 30 ends pivotally support opposing clutch jaws 8, held normally closed by a spring 9, and formed on their proximate faces with notches 10.

Supporting rollers 11 are mounted in line 35 on the table adjacent the openings 4, and a similar roller 12 is carried by the pull-frame cross-bar 7, the arrangement being such that the rollers 11 and 12 are in the same vertical plane.

40 A cylinder 13 is supported adjacent the table, and the piston therein operated in either direction as desired, by fluid pressure, such as air under pressure delivered through either of two supply pipes 14 and 15. The 45 piston 16 in said cylinder has its rod 17 formed with a wedge terminal 18, and this wedge is adapted to bear in movement between the rollers 11 and 12 as will be evident.

50 A pin 19 is adapted to be passed through aligned openings 20 in the plates to be drawn together, as 21, 22, and headed or otherwise held against withdrawal movement. The upper end of the pin is headed at 23, for 55 cooperation with the clutch jaws 8. The

respective uprights 2 are preferably of unequal lengths so as to provide bearing for the base on the respective plates as they are drawn into position.

With the parts assembled as described, it is evident that movement of the wedge 18 in one direction, will force the pull frame upwardly and draw plates 21, 22 together. They may be held in this position by the wedge until the contemplated work is completed, when reverse movement of the wedge under suitable fluid pressure admission to the cylinder, will withdraw the wedge, permitting the pull frame to move downwardly and releasing the clutch jaws from the pin 19.

Having thus described the invention what is claimed as new is:

1. A plate assembling machine, comprising a base, a pull-frame movable therein, clutch jaws carried by the pull-frame, and a wedge for operating the pull-frame and bearing rollers for said wedge carried by the base and pull-frame. 75

2. A plate assembling machine, comprising a base, a pull-frame movable therein, clutch jaws carried by the pull-frame, and a wedge for operating the pull-frame and fluid pressure means for operating said wedge. 80

3. A plate assembling machine comprising a base formed with laterally extending legs, the base also being formed with openings therein, a pair of rollers mounted on the base adjacent the openings, a pull-frame movable therein including a pair of rods extending through said openings and connected at their upper ends by a cross-bar, opposing clutch jaws mounted on the lower ends of the rods, resilient means normally closing the jaws, a roller mounted on the cross-bar and in line with the first-mentioned rollers, a wedge adapted to engage the rollers for operating the pull-frame and fluid-pressure means for operating the wedge. 90

4. A plate assembling machine comprising a base formed with laterally projecting legs, a pull-frame movable in the base formed with parallel rods adapted to slide in openings in the base, means carried by the rods to connect the pull-frame with a plate, a cross-bar connecting the rods, rollers mounted on the base, a roller mounted on the cross-bar and a wedge adapted to engage 105

between the rollers for operating the pull-frame.

5. A plate assembling machine comprising a base formed with laterally projecting legs, a pull-frame slidable in the base formed with parallel rods adapted to slide in openings in the base, clutch jaws carried by the

rods, a cross-bar connecting the rods, rollers carried by the base, a roller mounted on the cross-bar, a wedge adapted to engage between the rollers and fluid-pressure means for operating the wedge and the pull-frame. 10

In testimony whereof I affix my signature.

FRED N. HALLETT.
